US00D572048S

(12) **United States Design Patent**
Weimer et al.

(10) **Patent No.:** **US D572,048 S**
(45) **Date of Patent:** **** Jul. 1, 2008**

(54) **BENCH SUPPORT**

(75) Inventors: **Kent Weimer**, Columbia City, IN (US);
Douglas Garofalo, Chicago, IL (US);
Grant Gibson, Chicago, IL (US)

(73) Assignee: **Wabash Valley Mfg., Inc**, Silver Lake,
IN (US)

(**) Term: **14 Years**

(21) Appl. No.: **29/288,673**

(22) Filed: **Jun. 19, 2007**

(51) **LOC (8) Cl.** **06-01**

(52) **U.S. Cl.** **D6/492**

(58) **Field of Classification Search** D6/334,
D6/335, 341, 349, 353, 354, 377, 367-369,
D6/381, 383, 491, 500-502; 297/16.1, 16.2,
297/232, 245, 283.2, 353, 354.1, 445.1, 448.1;
5/12.1, 12.2
